UNITED STATES PATENT OFFICE.

DAVID D. GORDON, OF CHICAGO, ILLINOIS, ASSIGNOR, BY MESNE ASSIGNMENTS, TO
CENTRAL WEST ELECTRIC CO., OF CHICAGO, ILLINOIS, A CORPORATION OF ILLINOIS.

MECHANICAL MOVEMENT.

1,180,642.

Specification of Letters Patent. Patented Apr. 25, 1916.

Application filed November 24, 1913. Serial No. 802,795.

To all whom it may concern:

Be it known that I, DAVID D. GORDON, a citizen of the United States, residing at Chicago, in the county of Cook and State of Illinois, have invented a certain new and useful Improvement in Mechanical Movements, of which the following is a full, clear, concise, and exact description, reference being had to the accompanying drawings, forming a part of this specification.

My invention relates to switching devices and has for its object to provide an improved mechanical movement for such or similar devices.

The movement illustrated herein has, as stated, a variety of uses but it is of particular utility, for instance, in connection with a switching device and is of use in connection with a socket or pendant switch or such similar structure.

The application of my invention will be understood, of course, with whatever device it may be associated, but I have decided herein to illustrate my invention in connection with a socket and a pendant switch, and the description herein will be confined specifically to these devices as it is thought they will readily illustrate the nature of my invention.

It is the object of my invention, for instance, to provide a mechanical movement for a switch in which a suitable actuating lever or handle is provided which may be rotated forwardly or backwardly, of the reciprocating variety, and which may effect a snap action movement of a switch element both for circuit closure and circuit opening irrespective of the direction of movement of the handle or other operating device.

My invention is designed to provide a simple movement of the above character, and I will explain it more in detail by referring to the accompanying drawing illustrating the same as applied to a socket and pendant switch, in which—

Figure 1 is a longitudinal sectional view of a socket constructed in accordance with my invention; Fig. 2 is a top plan view of the operating mechanism shown in Fig. 1 with the cap shell removed; Fig. 3 is a longitudinal sectional view of a pendant switch constructed in accordance with my invention; Fig. 4 is a sectional view on line

b—b of Fig. 3, and Fig. 5 shows the structure of Fig. 1 in its alternative form.

Referring more particularly to Figs. 1, 2 and 5 I illustrate a socket having a normally screw threaded contact member 1 and the central contact member 2. The screw threaded contact member is connected by means of a binding post 3 to the entering wire 4, whereas the other entering wire 5 is connected by means of a binding post 6 to a switch element 7. This switch element is pivoted at 6, if desired, and is movable between limit stops 8 and 9. In its position against the stop 8 the switch element 7 makes contact with a contact element 10 connected directly to the central contact member 2, thus completing the circuit from the wires 4 and 5 to the lamp socket terminals. When the switch element 7 is in its alternative position resting against the stop 9, then the circuit through the socket is open as will be readily apparent.

Now in order to move the switch element 7 by snap action both to make and break the circuit, I provide a handle 11 pivoted in posts 12 and 13 as shown, which has a crank 14, which crank has a spring 15 coiled about it, the free ends of which spring then extend substantially parallel, one of the extremities 16 resting against the screw 6 in the particular embodiment shown and slideable along said screw, and the other leg 17 of said spring being bent V shaped and resting against the shank of a screw 18. The heads of the screws 18 and 6, of course, serve also to prevent displacement of these spring arms.

Now assume that the parts are in the position of Fig. 1 and the handle 11 is turned either clockwise or contra-clockwise. Whichever direction of movement is made the spring will ultimately be drawn toward the left until the apex of the triangular portion of the leg 17 passes the screw 18, at which time the spring presses the element 7 toward the right as will be readily apparent because the screw then slides along the other face of the angular portion of the spring. As the legs 16 and 17 are not exactly in line, they will clear during this movement.

It is of course understood that the tendency of the legs 16 and 17 is to separate, the action of the spring being in that direction.

The circuit is thus opened. Now should it be desired to close the circuit, thereby pushing the spring 15 to the right until the apex of the angular portion again passes beyond the screw 18, at which time the inclined surface acting against the screw 18 will force the switch element back to the position shown in Fig. 1.

Referring more particularly to Figs. 3 and 4, I show my device applied to a pendant switch having the two insulating elements 19 and 20 adapted for screw threaded engagement as shown at 21. A movable element 22 is pivoted as shown at 23 and is adapted to make contact with two contact posts 24 connected respectively to the lead in wires 25, but insulated from each other. The movable element 22 occupies either the position shown in Fig. 3 against the limit stop 26 or an alternative position against the stop 27, in which lower position it closes circuit through the wires 25, 25. This arm 22 has an extending bracket 28 which might be likened to the screw 18 of Fig. 1, and which is adapted to coöperate with a spring 29 mounted upon a screw 30 forming part of the reciprocating plunger 31. This spring 29 by being slid either to the right or to the left causes the actuation of the contact element 22 similarly to the actuation of the element 7 of Fig. 1. A stop 32 confines the movement of the plunger within its receptacle.

I have thus shown and particularly described two embodiments which my invention may take, but it will be readily clear to those skilled in the art that my invention is capable of various applications.

Having however thus described two forms of my invention, what I claim as new and desire to secure by Letters Patent is:

1. In a switch the combination of having a pivoted oscillatory switch arm, resilient reciprocatory means engaging said arm to move the same by snap action from either limiting position to the other, and

means to reciprocate said reciprocatory means, said reciprocatory means consisting of a U-shaped spring.

2. In a switch the combination of having a pivoted oscillatory switch arm, resilient reciprocatory means engaging said arm to move the same by snap action from either limiting position to the other, and means to reciprocate said reciprocatory means, said reciprocatory means consisting of a U-shaped spring, bent at its arm engaging extremity to form a V-shaped cam.

3. In a switch the combination of having a pivoted oscillatory switch arm, resilient reciprocatory means engaging said arm to move the same by snap action either from limiting position to the other, and a crank to reciprocate said reciprocatory means, said reciprocatory means consisting of a U-shaped spring.

4. In a switch the combination of having a pivoted oscillatory switch arm, resilient reciprocatory means engaging said arm to move the same by snap action from either limiting position to the other, and a crank to reciprocate said reciprocatory means, said reciprocatory means consisting of a U-shaped spring bent at its arm engaging extremity to form a V-shaped cam.

5. In a switch the combination of having a pivoted oscillatory switch arm, resilient reciprocatory means engaging said arm to move the same by snap action from either limiting position to the other, and a crank to reciprocate said reciprocatory means, said reciprocatory means consisting of a U-shaped spring coiled about said crank bent at its arm engaging extremity to form a V-shaped cam.

In witness whereof, I hereunto subscribe my name this 21st day of November, A. D. 1913.

DAVID D. GORDON.
